[21] Appl. No.: **726,551**

CLAIM

[22] Filed: **Sep. 27, 1976**

The ornamental design for a roller conveyor belt, as shown and described.

DESCRIPTION

[51] Int. Cl. .... **D12—60**

FIG. 1 is a fragmentary plan view of the roller conveyor belt showing my new design, the belt being fragmentarily shown for convenience of illustration; and FIG. 2 is an axonometric view of the roller conveyor belt of FIG. 1.
